CANDELABRA

Bertil Vallien, Afors, Sweden, assignor to Dansk
Designs, Ltd., Mount Kisco, N.Y.

Filed May 26, 1970, Ser. No. 23,150

Term of patent 14 years

Int. Cl. D26—05

U.S. Cl. D48—2

FIG. 1

FIG. 2

FIG. 3

FIG. 4

FIG. 1 is a top plan view of a candelabra embodying my new design;

FIG. 2 is a side elevational view thereof;

FIG. 3 is an end elevational view thereof; and
FIG. 4 is a bottom plan view thereof.

I claim:

The ornamental design for a candelabra, as shown.
